CLAIM

The ornamental design for an IV clip, as shown and described.

DESCRIPTION

FIG. 1 is a top, rear, and left side perspective view of an IV clip;

FIG. 2 is a top, front, and right side perspective view of the IV clip of FIG. 1;

FIG. 3 is a top plan view of the IV clip of FIG. 1;

FIG. 4 is a bottom plan view of the IV clip of FIG. 1;

FIG. 5 is a front elevational view of the IV clip of FIG. 1;

FIG. 6 is a rear elevational view of the IV clip of FIG. 1;

FIG. 7 is a left side elevational view of the IV clip of FIG. 1 which is a mirror image of the right side elevational view; and,

FIG. 8 is a detailed environmental view of the IV clip of FIG. 1 in use with the IV clip attached to an IV line.

The dashed lines are only used to show the environment in FIG. 8 and form no part of the claimed invention.

1 Claim, 6 Drawing Sheets
